UNITED STATES PATENT OFFICE.

CLARENCE D. PLATT, OF BRIDGEPORT, CONNECTICUT.

PUSH-BUTTON SWITCH.

1,227,195.

Specification of Letters Patent. Patented May 22, 1917.

Application filed March 17, 1914. Serial No. 825,221.

To all whom it may concern:

Be it known that I, CLARENCE D. PLATT, a citizen of the United States, and a resident of Bridgeport, in the county of Fairfield and State of Connecticut, have invented 5 certain new and useful Improvements in Push-Button Switches, of which the following is a full, clear, and exact description, whereby any one skilled in the art may make 10 and use the same.

The invention relates to electric switches and more particularly to the type of switch known in the art as a push button switch. This may be of single or multiple pole de- 15 sign.

The class of devices referred to is well known as a type in the arts. The invention herein defined has to do particularly with a simplified and refined construction which 20 will provide a maximum strength, simplicity, a minimum number of parts and certainty of correct operation. The parts are so arranged and designed that they may be formed from dies with great accuracy, thus 25 providing ease of manufacture, to say nothing of advantages in assembly and subsequent operation.

The objects of the invention are to provide a supporting frame in which the moving parts may be readily assembled with accuracy and precision and with locking and releasing features for the switch blade, members having features of positive interlocking 30 without employment of cams or tension 35 springs.

A further object is to provide a switch bar carrier stamped up in a single piece and with bearings to minimize friction. A further object is to provide a slide bar and interlock for the switch bearing member or 40 yoke which will be positive in its locking and releasing actions and will operate without lost motions upon the operating buttons and switch blade carrying member.

45 Referring to the drawings

Figure 1 is a top plan view with the plate removed.

Fig. 2 is a cross sectional view on the line 2—2 of Fig. 1.

50 Fig. 3 is a similar cross-sectional view on the line 3—3 of Fig. 1.

Fig. 4 is a longitudinal section on the line 4—4 of Fig. 1.

55 Fig. 5 is a similar sectional view on the line 5—5 of Fig. 1.

Fig. 6 is a perspective view of the several switch parts in relative position for assembly.

Fig. 7 is a perspective view of the insulating receptacle.

Fig. 8 is a detail view of the switch blade yoke.

In devices of the character described, it is very desirable to reduce the number of moving parts to a minimum and to eliminate as far as possible tension springs for the pawls and detents inasmuch as the breaking down of the detent device for interlocking destroys the usefulness of the switch. In the present invention, provision 70 has been made for ready assembly of all the parts as a complete unit so that these parts may be inserted in an insulated box or casting of ordinary type. The supporting frame with all of the parts may be removed 75 at an instant's notice and the various parts may be disassembled from the supporting frame without the use of tools. Furthermore, there are no spring detents or spring 80 actuated locking devices for the switch blade or its appurtenant parts. The main spring for tensioning the switch blades is the only one employed in the device.

Referring to the drawings, the numeral 1 denotes the insulating casing ordinarily 85 formed from porcelain and containing the stationary contact members 2 which are provided with the usual line wire connections.

It is desirable in push button switches to provide a receptacle with as little depth as 90 possible and yet provide a sufficient throw for the switch blades and actuating mechanism. The device herein disclosed contains these advantages which are made possible 95 by mounting the switch mechanism at the extreme bottom of a supporting frame 3. This permits carrying the switch parts very close to the bottom of the receptacle. This frame 3 is preferably stamped up from sheet metal and is provided with the usual attachment ears 4 and perforations 5, 6 for the push buttons 7 and 8.

Depending from the upper bar of the frame are two parallelly disposed downwardly extending arms 9, 10 which have a 105 pivot perforation 11 adjacent to their lower ends upon which pivot, the moving parts of the mechanism are mounted.

The lower end of the dependent members 9 and 10 are provided with stop shoulders 110

12, 13 which limit the movement of a yoke 14 which supports the movable contact blades 15.

One of the dependent members as 9 has a guide slot 16 through which projects a stop lug 17 preferably struck up from sheet metal at one side of a slide member 18 which has an arm 19 and a transverse member 20, the latter practically filling the space between the two dependent members 9 and 10. The end of the transverse member 20 is cut away to give two bearing surfaces 21, 22 against the inside of the member 10, thus reducing the contact and consequent friction of the part as it slides between the members 9 and 10. The lug 17 is disposed in a line substantially midway between the contact points 21, 22 and therefore there is little tendency of the lug 17 binding in the elongated slide slot 16 through which it projects. The lower end of the member 19 is perforated as at 23 and engages a pivot stud 24 arranged upon the actuator bar 25. This actuator bar is provided with the usual pivotal connections 26, 27 for the push buttons 7, 8 and has a spring barrel 28 which gives ample bearing surface for the member 25 and acts as a retainer for the spring 29.

When this actuating bar 25 is in place, the pivot stud 24 projects toward the dependent plate member 9 and holds the member 19 of the slide plate in position against the inner face of the dependent member 9. As the stud 24 is at one side of the central bearing of the plate 25 an oscillation of said plate will move the slide member 18 between the plates 9 and 10 with a reciprocating motion. The stop lug 17 projecting through the slot 16 will, of course also move with a vertical reciprocation. Each reciprocation of the locking member or plate 18, due to an operation of the actuator bar 25, carries the stop lug 17 either above or below the lugs 34, 35. The releasing movements are therefore effected by under and over movements of the locking or stop lug 17, with reference to the lugs 34 and 35. Inasmuch as the locking plate bearing the stop lug 17 is directly pivoted to the actuator bar 25 at one side of the pivotal center of the latter, it is apparent that upon the release of the lugs 34 and 35, by either the raising or depression of the stop lug 17, there is a full and instant release upon the completion of each movement of the actuator bar. Such movement of the actuator bar carries the lug 25 slightly beyond the position occupied by the cross piece 14 of the yoke, when the latter is arrested by the stop shoulders, either 12 or 13, 60 with spring 29 still under some tension; so that it follows that upon the release of the actuator bar, through the operator taking his finger from the push button, there is an immediate relocking of the parts through 65 the spring operating to bring the lug 25 of

the actuator bar into parallelism with the cross piece 14 of the yoke. This latter movement, by reason of the direct pivotal connection between the actuator bar and the locking slide member or plate 18 insures that the locking or stop lug 17 shall be brought into the path of the lug 34 or 35 of the yoke, thus positively relocking the parts. This arrangement is a distinct advancement over the prior art, so far as known, in simplicity of construction and positiveness of operation, inasmuch as there is no camming action between the parts such as has heretofore been resorted to in electric switches of the kind to which mine belongs.

The contact blades 15 are mounted upon the yoke 14 and insulated therefrom in a manner well-known in the art.

The yoke 14 is preferably formed by stamping up from sheet metal and has axially aligned perforations 30, 31 in its respective arms 32, 33. The arm 32 at its upper end has in-turned locking lugs 34, 35 which are angularly disposed with reference to the bar 32, the angularity being such that the lugs are practically parallel with the slot 16 and projecting stop lug 17 when the yoke is at either limit of its play.

The perforations 30, 31 are stamped through the upwardly extending arms 32, 33 of the yoke 14 and thus provide elongated bearing surfaces for the yoke with practically knife-edge bearing points 36 where they engage the sides of the dependent members 9 and 10. These bosses 36 serve as 100 definite spacers for the yoke 14 and as described, have a maximum strength and bearing surface with a minimum frictional wear against the dependent wearing members 9 and 10.

The actuating plate 25, together with the yoke member and appurtenant parts are mounted upon a spindle 37 and this spindle is of the floating type and is held in position when the parts are assembled in the receptacle by the side walls of the receptacle.

As illustrated, the receptacle 1 is provided with grooves 38, 39 on its opposite sides and as the assembled switch mechanism is inserted in the receptacle, the floating pin 37 is held against axial movement by the walls of the receptacle. This arrangement obviates riveting and especially over-riveting and setting of the parts which will tend to interfere with their freedom of action. It also provides a ready means for taking down the switch mechanism for inspection or repairs. The spindle 37 is preferably pointed at one end so that it will readily find its way through the various perforated parts supported upon it or upon which it is supported.

The spring 29 upon the drum 28 of the actuating bar 25 is of the two-arm type and its arms extend on either side of a lug 25^a which projects laterally of the plate 25. 130

When assembled, the spring arms are just sufficiently separated to permit the insertion of the cross bar of the yoke 14 between them.

To assemble the device, the slide-plate 18 is first inserted between the plates 9, 10 with its stop lug 17 projecting through the slot 16. The pivot stud 24 is then engaged with the perforation 23 of the member 19.

The yoke member 14 upon which are assembled the switch bars 15 is then placed in position with its bar resting between the two arms of the spring 29 and its perforations at substantial registration with the perforations 11 of the plates 9 and 10. The supporting spindle 37 is then inserted through all the parts.

When assembled, one or the other of the stop lugs 34, 35 rests against the side of the projecting stop lug 17. As the respective push buttons are depressed, the stop lug 17 is moved downwardly by the oscillating movement imparted to the plate 25 and at the same time, the spring 29 is placed under tension due to the movement of the lug 25 away from its registering position with the yoke member 14. When the spring is under full tension, the lug 17 has moved sufficiently to free the lug 34 or 35 of the yoke member and thereupon the yoke member will oscillate with great rapidity under tension of the spring 29 until its lower cross bar is brought against one of the stops 12, 13.

It will be noted from the above description of the parts that the yoke member has a bearing at either end which is outside of the dependent frame member and that the stops of the dependent frame coöperate with the yoke at both sides. This arrangement gives in effect an extremely long bearing 40 for the yoke member so that there is little or no tendency of its twisting when under strain.

Attention is also particularly called to the slide plate 18 with its detent member. This slide plate filling the space between the dependent members of the supporting plate provides a long bearing which precludes any possibility of the slide member cramping upon the pivot stud which operates it.

Obviously, the exact detail and arrangement of the parts might be varied to a considerable extent without departing from the spirit or intent of the invention but it is apparent that the device as illustrated and described relies upon a single main spring 55 without spring detents or rotary cams for

locking and releasing the switch blades. Provision is made to minimize friction and contact surface of the moving parts and the locking and releasing actions are positive 60 and are derived directly from the switch actuating member.

What I claim as my invention and desire to secure by Letters Patent is:

1. In a push button switch, a supporting 65 plate having dependent parallel members provided with stop lugs, a switch blade yoke embracing said members, a slot formed in one of said dependent members, a slide plate extending between said members from one to 70 the other and guided thereby and having a lug projecting beyond one of said dependent members, a spring intermediate said actuator and switch blade yoke and a pivotal connection intermediate the actuator and slide plate 75 for reciprocating the latter.

2. In a push button switch having a supporting plate with parallel dependent members, a slot formed through one of said members, a slide plate extending between 80 the dependent members of the supporting plate and with an arm formed integral therewith and resting against one of said members, an oscillatory actuator pivotally connected with said arm, a lug extending from 85 the slide plate through the slot of the dependent member and a switch blade yoke controlled by said lug.

3. In a push button switch having a supporting plate with parallel depending members, a reciprocating slide plate located between said members and extending across from one to the other so as to have supporting bearing against each, a locking and release lug carried by the said plate, and an 90 oscillatory actuator for the said plate.

4. In a push button switch having a supporting plate with parallel dependent members, a slide plate extending between the dependent members of the supporting plate 110 and bearing against both of said members and having an arm resting against one of said members and extending to an actuating member, an oscillatory actuating member having a pivotal connection with said arm, a 105 lug extending from the slide plate, and a switch blade yoke having stop lugs engaging the extended lug of the slide plate.
